UNITED STATES PATENT OFFICE

JOHN H. BURPEE, OF BELLINGHAM, WASHINGTON, ASSIGNOR TO E. B. FOSTER AND
CECIL A. FOLSOM, OF BELLINGHAM, WASHINGTON

CAN CONVEYER

Application filed April 7, 1931. Serial No. 528,255.

My invention relates to improvements in can conveyers, and has for an object to provide overlapping conveyer plates for an endless-chain conveyer which nearly cover the

5 bottom of the passageway in which they move whether the same be straight or curved.

Another object of my improvement is to provide overlapping chain-conveyer plates engaged with each other in chain relation to 10 cause individual feathering thereof.

Another object of my improvement is to provide oblong, overlapping, eccentrically-pivoted, chain-conveyer plates engaged with each other in chain relation to cause individual feathering thereof.

Another object of my improvement is to provide oblong, overlapping, eccentrically-pivoted, chain-conveyer plates engaged in chain relation for varying spacing.

20 Another object of my improvement is to provide overlapping, chain-conveyer plates for carrying cans around bends adapted to avoid catching hold of said cans although the same are relatively large and small.

25 Another object of my improvement is to provide a pivoted take-up device to maintain operative tension throughout the chain of the conveyer.

Other objects of my improvement will appear as the description proceeds.

I attain these and other objects of my improvement with the mechanism illustrated in the accompanying sheet of drawings, which form a part of this specification, in which Figure 1 is a plan view of my conveyer in place in a cooking tank the cover of which is removed and having a large central section broken away for lack of space for the drawings, Fig. 2 is a side elevation of Fig. 1 in section on the bent line 2—2 thereof, Fig. 3 is the front end elevation of Fig. 2, Fig. 4 is an edge elevation of one of the similar conveyer plates segregated, Fig. 5 is a bottom plan view of Fig. 4, Fig. 6 is a bottom plan view of another form of the conveyer plates, Fig. 7 is a side elevation of the movable end guide as attached to the chain-take-up lever, and Fig. 8 is a plan view of the pivoted take-up lever segregated.

Similar characters refer to similar parts throughout and certain parts are broken away for lack of space or to show other parts hidden thereby.

With more particular reference to the 55 designated parts: A tank 9, which in practice may be thirty or more feet long, has a water-seal top edge 10 and is provided with cover 11 having a flanged edge to fit in the seal.

60 There are three frame bars fastened longitudinally within the tank of which the center one 12 is confined to the tank while the rear-side bar 13 and the front-side bar 14 extend the full length of the tank and are 65 extended through openings in the front tank wall and project beyond the same.

Drive sprocket wheel 15 is fastened on shaft 16 which is mounted for revolution in vertical bearing 17 fastened to bar 13 external to the tank. Lead sprocket wheel 18 is fastened to shaft 19 which is mounted for revolution in a vertical bearing fastened on bar 13 near the rear end of the tank and within the same in chain relation with 70 sprocket 15. Lead sprocket wheel 25 is fastened to shaft 26 and the shaft is mounted for revolution in a vertical bearing 21 fastened midway on take-up lever 20. Take-up 75 lever 20 is pivoted at 22 to bracket arm a12 on bar 12 and has eye 24 fastened on the front side of its free end and lug 23 on its front side midway thereof. Bearing 21 is disposed to mount sprocket 25 in chain relation with sprocket 18. Lead sprocket wheel 27 is fastened on shaft 28, which is mounted for revolution in vertical bearing 29 on the front end of bar 14 external to the tank, in chain 80 relation with sprocket 15. Lead sprocket 30 is fastened on shaft 31 which is mounted for revolution in vertical bearing 32 on bar 14 within the tank near the rear end thereof. Sprocket 30 is disposed in chain relation with sprockets 25 and 27.

Conveyer chain 33 is engaged with all of 95 said sprocket wheels to provide a single fold thereof external to the tank at the front end thereof and a double fold within the tank extending through openings 42 and 43 in the front wall of the tank. Chain 33 is com- 100

posed of a number of groups of three links each joined in the usual conveyer chain manner and said groups are joined in hinge relation by plate pins 34 thus equally spacing 5 said pins. Pins 34 protrude beneath the chain where each has a removable key pin extended through an opening therein to prevent said hinge pins from moving upward out of operative position. Said hinge pins 34 10 also protrude above the chain and each has welded to its upper end one of conveyer plates 35. As shown the upper end $\alpha 34$ of the pin is flattened to a head and welded in a hole in said plate. This construction is used 15 for the benefit of the illustration, but in practice the butt end of the pin is welded on the bottom side of the plate leaving the top thereof smooth.

Each of plates 35 is preferably oblong and 20 pin 34 is fastened near one end thereof while in the other end thereof is deep notch 36 through which is extended pin 34 of the overlying plate 35 as shown in Figs. 1 and 2. Notch 36 is deep enough to provide for the 25 nearer approach of pins 34 in passing over a sprocket wheel when adjacent pins are in the chord of an arc in which the chain therebetween is held. This relation is clearly shown in Fig. 1 on sprocket wheel 30 where the adjacent pins engaged by the sprocket are nearer together than on the straight parts of the chain between the sprocket wheels. Notch 36 is deep enough to accommodate this described nearer approach of the pins when 30 passing over the sprocket wheels, as stated. In Fig. 6 is shown a conveyer plate $\alpha 35$ in which slot $\alpha 36$ replaces notch 36 described. Slot $\alpha 36$ is long enough and disposed to accommodate the pin 34 of the overlying plate 40 when chain 33 is straight and also when it is curved over a sprocket wheel. Plate $\alpha 35$ is preferred over plate 35 when the required quantity of conveyer plates makes stamping thereof desirable. The width of notch 36 45 and slot $\alpha 36$ is only sufficient to allow one of pins 34 to operate therein, and the engagement of the hinge pin of each conveyer plate in the opening in the underlying plate couples the several plates in articulative chain relation. The preferred shape of the conveyer plates is oval, as illustrated, in that the external-edge contour thereof may be substantially concentric with the sprocket wheels as they turn about the same. As usual in such 50 structures, one of pins 34 must be disengagable from its plate in order that the chain may be coupled in continuous relation and uncoupled therefrom.

A removable hinge pin chosen for the illustration is shown at $\epsilon 34$ in Fig. 1 extended through plate reinforcement $\beta 34$ on plate $\beta 35$. Said reinforcement is preferably made by using a washer with a beveled edge and a countersunk hole to register with the pin hole 55 in the plate. The washer is welded to the

plate and the head of the pin is very thin with beveled edge and has an integral key thereon to engage in a keyseat in the washer.

One edge of the chain of conveyer plates is supported on the horizontal flange of angle bar 37 which begins at chute 40 passes through tank opening 42 and continues to follow the tortuous course of the chain of plates through the tank and passes out through tank opening 43 to connect with chute 41. The vertical flange of this angle bar provides a wall to guide the cans passing through the tank. The other edge of the chain of plates is supported on the horizontal flange of angle bar 38 which begins at $\alpha 38$ adjacent tightener 70 sprocket wheel 25, best shown in Fig. 1, and follows the course of the chain of plates through the tank which it leaves through opening 42 therein to follow the same edge of the chain of plates external to the tank which 75 it again enters through opening 43 to continue alongside the plates till sprocket wheel 25 is again reached where it terminates at $\beta 38$. The vertical flange of angle bar 38 provides a wall to guide the cans passing through 80 the tank. Both angle bars are supported on brackets fastened to the tank and to bar 12 and also they are fastened to the tank wall where they pass therethrough. Three of said 85 supporting brackets are shown at $\alpha 37$, $\alpha 37$ 90 and $\beta 37$. The horizontal flange of angle bar 39 supports the outer edges of said chain of plates passing from chute 41 to chute 40 external to the tank, and the vertical flange thereof provides a wall for cans on said 95 plates. Angle bar 39 is fastened to said 100 chutes.

Cans are delivered to the tank through chute 40 leading to the chain of conveyer plates which enter said tank through opening 105 42 in the front end thereof. Said cans are delivered by said conveyer plates through opening 43 in said front end of the tank into chute 41 after having followed the chain of conveyer plates through its entire course 110 within the tank.

Cord 44 is fastened in eye 24 on the free end of take-up lever 20 and is extended through an opening in the front end of the tank where it passes over sheave 45, which is 115 mounted for revolution on an axle bolt fastened to the outside end of bar 14, and has weight 46 fastened to its outer end to maintain take-up pressure on sprocket wheel 25 and conveyer chain 33 thereover.

The lower end of frame 47 is pivoted to lug 23 on take-up lever 20, extends forward and then upward to provide support for semicircular guard rail 49. Said guard rail is fastened to frame 47 to dispose the guard rail 125 adjacent and forward of the central front fold of the chain of conveyer discs to guard the cans moving thereon. Frame 47 is extended rearward and downward at $\alpha 47$ to engage with guide 50 in which it may recipro- 130

cate to maintain guard 49 properly disposed relative to said discs as lever 20 oscillates on cap screw 22.

Bevel gear 51 is fastened on the bottom end 5 of sprocket shaft 16. Bearing 54 is fastened on the front end of the tank and mounts shaft 53 for revolution disposed to engage bevel gear 52 fastened thereon with bevel gear 51 described. On shaft 53 also is fastened drive 10 pulley 55 adapted to be driven from a prime mover not shown. The construction providing for the driving of chain 33 and plates 35 by pulley 55.

Pipe 56 is extended through an opening in 15 the tank and lies on or near the bottom thereof. Within the tank the pipe is perforated. It is connected with a source of steam, not shown.

The illustration is of a vegetable cooker 20 and the conveyer is operated slowly to allow cans of vegetables carried through the tank thereon to receive initial cooking from the heat of steam therein prior to sealing the tops thereof.

25 My conveyer is well suited for the objects illustrated and described as well as many other uses where articles are to be carried on chain conveyers.

Having thus disclosed my invention, what 30 I claim as new therein and desire to secure by Letters Patent is,—

1. The conveyer chain of an endless chain conveyer including a closed chain of links engageable with sprocket wheels and having 35 hinge pins protruding from one edge thereof, and an endless chain of overlapping conveyer plates each having an elongated opening therein near one end thereof through which extends one of said protruding hinge pins and being fastened near its other end to the end of another of said protruding hinge pins.

2. The conveyer chain of an endless chain conveyer including a closed chain of links 45 engageable with sprocket wheels, hinge pins mounting spaced joints of said chain for articulation protruding from one edge thereof, and an endless chain of conveyer plates each having an elongated opening therein 50 near one end thereof and the other end thereof being fastened to the protruding end of one of said hinge pins said pin being extended through said elongated opening in an adjacent one of said conveyer plates.

55 3. An endless chain conveyer including a drive sprocket wheel and lead sprocket wheels mounted in chain relation for revolution, an endless chain engageable with said sprocket wheels mounted thereon to be driven thereby, 60 hinge pins mounting spaced joints of said chain for articulation protruding from one edge thereof, overlapping conveyer plates each having an elongated opening therein near one end thereof through which is extended the protruding end of one of said hinge

pins and the protruding end of another of said hinge pins being fastened to one side of said plate near the other end thereof and extended through said elongated opening in an adjacent one of said plates, and connections between said drive sprocket wheel and a source of power.

4. An endless chain conveyer including a drive sprocket wheel and lead sprocket wheels 70 mounted for revolution disposed in chain relation one of said lead sprocket wheels being mounted for said revolution on a take-up lever for oscillation therewith, means to pivot one end of said take-up lever for oscillation, a counterweight connected to the other end of said take-up lever to pull the same tightening a conveyer chain mounted on said sprocket wheels, said conveyer chain mounted on said sprocket wheels to be driven thereby 80 having hinge pins protruding from one edge thereof, and an endless chain of overlapping conveyer plates each having an elongated opening therein near one end thereof through which extends one of said protruding hinge pins and being fastened near its other end to the end of another one of said protruding hinge pins.
